GEORGE KABACIJ AND ANDREW BARTUS, OF WYATT, WEST VIRGINIA.

ANTISLIPPING DEVICE.

1,378,962.

Specification of Letters Patent. Patented May 24, 1921.

Application filed August 24, 1920. Serial No. 405,612.

To all whom it may concern:

Be it known that we, GEORGE KABACIJ and ANDREW BARTUS, citizens of Hungary and the United States, respectively, residing at 5 Wyatt, in the county of Harrison and State of West Virginia, have invented certain new and useful Improvements in Antislipping Devices, of which the following is a specification.

10 This invention relates to an anti-slipping device for boots or shoes which is adapted to be applied to the heel of the shoe to enable the user to walk safely on icy pavements, walks or other surfaces.

15 The invention has for an object to provide a simple and inexpensive device of this kind which may be used in connection with any ordinary heel and attached and detached as desired.

20 For further comprehension of the invention, and of the objects and advantages thereof, reference will be had to the following description and accompanying drawings, and to the appended claims in which the various

25 novel features of the invention are more particularly set forth.

Figure 1 of the drawings is a perspective view of an anti-slipping device constructed according to our invention.

30 Fig. 2 is a fragmentary horizontal section taken on the line 2—2 of Fig. 3.

Fig. 3 is a transverse section through the front portion of the device along the line 3—3 of Fig. 1.

35 As here shown our improved device comprises briefly a plate element adapted to fit upon the heel of the shoe and divided longitudinally into a pair of sections 1 and 2, the two sections jointly corresponding in outline 40 to the heel of the shoe. These sections have upstanding flanges, 3 and 4 respectively, extending around the side and curved rear edge thereof, these flanges being hinged together at the rear of the plate element as at 5 where- 45 by the two sections may be opened or closed toward one another, the flanges 3 and 4 constituting in effect a pair of jaws which grip the heel.

In order to enable the device to be fitted on 50 heels of different sizes the adjacent edges of the sections 1 and 2 are preferably arranged to diverge slightly away from one another from the hinged rear end forwardly, as shown in Fig. 1, downwardly projecting 55 spikes 6 and 7 being formed on these sections adjacent these inner edges.

In connection with our improved device we employ a novel clamping means for securing it upon a heel. This means comprises a tie bar 8 which extends between the flanges 3 and 4 at the front end of the device and is capable of bodily adjustment transversely to itself for application to heels of different sizes. To this end the flanges 3 and 4 are formed with slots 9 and 10 extending rearwardly a distance from the front ends thereof. Formed in the flange 3 are a series of longitudinally spaced vertical borings 11 which intersect the slot 9. Projecting into these borings are the prongs 12 of a fork element 13, which prongs are adapted to serve as hinge pintles for one end of the bar 8. Each of these prongs is formed with a circumferential recess such as 14 which registers with the slot 9 when the fork is in place, 75 while the end of the bar 8 has an opening 15 therein of slightly larger diameter than the prongs 12, through which opening the selected one of the prongs passes.

The opposite end of the bar 8 has a fixed 80 pin extension 16 screwed thereinto which engages in the slot 10 in the flange 4 to which it is yieldingly secured by the following means. Upon this pin 16 is slidably mounted a cup shaped member 17 whose open end 85 faces outwardly and whose closed end is formed with a parti-spherical projection 18 adapted to engage in the desired one of a series of complementary recesses 19 on the outer face of the flange 4, these recesses 19 being positioned along the flange 4 in correspondence with the borings 11 in the flange 3. The projection 18 is pressed into engagement with the recesses 19 by a coiled expansion spring 20 surrounding the pin 16 in the 90 cup 17 and bearing between the closed end of said cup and the enlarged head 21 of the pin. As will be obvious, the spring 20 is pulling also on the bar 8 and its pressure acts to keep the wall of the perforation 15 in the 100 opposite end of the bar in engagement with the recess 14 in the prong of the fork 13, holding the latter against displacement.

It is believed that the manner of use of our 105 improved anti-slipping device will be apparent from the above description, it being obvious that the spring 20, acting through bar 8, will hold the flanges 3, 4 in gripping engagement with the sides of the heel. The bar 8 may be adjusted to accommodate different sized heels by partially pulling out the fork 13 and bringing the aperture 15 in the 110

bar into registry with the desired one of the prongs 12, the projection 18 on the cup 17 being engaged in the juxtaposed one of the recesses 19 in the flange 4 it being understood 5 that the bar 8 may be released from the recess 14 in the prong 12 by swinging the pin 17 out of the end of the slot 10 or pressing inwardly on the head of the pin 16.

Having thus described our invention what 10 we claim as new and desire to protect by Letters Patent of the United States is as follows:

1. An anti-slipping device comprising a pair of plate sections hinged together at one 15 end and provided with spikes, means on said plate sections adapted to grip the sides of a heel, a bar hinged at one end to the free end of one section, a member on the other end of the bar adapted to engage the other section to 20 cause the device to grip a heel, and a spring pressing said member against the said other section.

2. An anti-slipping device comprising a pair of hinged plate sections each having an 25 upstanding flange extending along the side and rear edge thereof, the flange on one section being slotted rearwardly for a distance from the front end thereof, a bar hinged at one end to the front end of the other flange 30 and adapted to be swung into and out of engagement with the said slot, a head slideable on the said bar, and a spring on said bar adapted to press said head against the said slotted flange.

3. An anti-slipping device comprising a 35 pair of plate sections each having an up- stand flange extending along the side and rear edge thereof said flanges having slots ex- tending rearwardly therein from the front 40 ends thereof, means hinging said sections to- gether at their rear ends, a locking bar ex- tending between the said flanges and engag-

ing in the said slots, and means providing for bodily adjustment of said bar transversely of itself to different locking positions. 45

4. An anti-slipping device comprising a pair of plate sections each having an up- standing flange extending along the side and rear edge thereof said flanges having slots extending rearwardly therein from the front 50 ends thereof, means hinging said sections to- gether at their rear ends, a locking bar ex- tending between the said flanges and engag- 55 ing in the said slots, and means providing for bodily adjustment of said bar trans- versely of itself to different locking positions, 60 said means including a fork element carried in one of said flanges and having a plurality of prongs adapted to serve as desired as hinge pintles for any end of the said bar. 65

5. An anti-slipping device comprising a pair of plate sections each having an up- standing flange extending along the side and rear edge thereof, said flanges having slots extending rearwardly therein from the front 65 ends thereof, means hinging said sections to- gether at their rear ends, a locking bar ex- tending between the said flanges and engag- 70 ing in the said slots, a fork element carried in one of said flanges and having a plurality 75 of prongs adapted to serve as desired as hinge pintles for one end of the said bar, said prongs having recesses in the sides thereof adapted to be engaged by the bar to hold the fork against displacement, and a device including a spring upon the opposite 80 end of the bar adapted to yieldingly hold the said end in engagement with the adjacent flange and the bar in engagement with the recess in the prong. 85

In testimony whereof we have affixed our signatures.

GEORGE KABACIJ.
ANDREW BARTUS.
